FRIDOLPH A. OLSON, OF MILWAUKEE, WISCONSIN

CASEMENT WINDOW AND HINGE THEREFOR

Application filed June 11, 1930. Serial No. 460,419.

This invention relates to improvements in casement windows and hinges therefor.

If a casement window is arranged so as to open or swing inwardly into a room to permit the mounting of a screen or storm sash for the window exteriorly of the window, which is desirable, it is impossible to provide a weather tight stop strip between the window casing and the lower edge of the casement window sash. On the other hand, if the casement window is mounted so as to swing outwardly, a stop strip may be arranged on the sill so as to have a rabbeted joint connection with the lower edge of the window sash and prevent the entrance of weather, but this arrangement necessitates the undesirable disposition of a screen for the window inwardly of the window.

It is, therefore, the primary object of the present invention to provide a casement window and hinges therefor whereby the casement window may be mounted to swing inwardly and still permit the mounting on the window sill of a stop strip which will tightly engage the lower edge of the window when the same is closed, and prove extremely weather-tight.

A further object of the invention is to provide window hinges which will permit slight movements of the window in a vertical plane.

A further object of the invention is to provide hinges which may be easily and quickly manipulated so as to prevent hinging movements of a window carried thereby and assisting in serving as locks for the door or window.

A further object of the invention is to provide a casement window and hinges therefor which are of very simple construction, are strong and durable, are inexpensive to manufacture and install, and are well adapted for the purposes described.

With the above and other objects in view the invention consists of the improved casement window and hinges therefor, and their parts and combinations as set forth in the claims, and all equivalents thereof.

In the accompanying drawings in which the same reference characters indicate the same parts in all of the views:

Fig. 1 is a front view of a window casing and casement window mounted therein by means of the improved hinges, the view being of the interior or inner surface of the casing and window;

Fig. 2 is a similar fragmentary view showing the window raised in a vertical plane to disengage the stop strip and the hinges adjusted to permit the inward swinging of the window;

Fig. 3 is a fragmentary detail sectional view taken on line 3-3 of Fig. 1;

Fig. 4 is an enlarged detail view of a hinge member in one position of adjustment;

Fig. 5 is an enlarged detail view of a hinge member in another position of adjustment; and

Fig. 6 is a longitudinal sectional view of the hinge member taken on line 6-6 of Fig. 4.

Referring now more particularly to the drawings it will appear that the numeral 8 indicates a window casing in which is mounted on hinge members generally indicated by the numerals 9 and 10, so as to swing inwardly, a glazed casement window 11. There is positioned on the sill of the window casing 8 a stop strip 12 and the inner lower edge of the frame or sash of the casement window 11 is rabbeted as at 13 to form a tight joint with the stop strip 12 when the window is in its normal closed position. Due to the fact that said stop strip is positioned so as to engage the inner portion of the window and is thereby weather proof and due to the fact that the window is mounted so as to swing inwardly, a stop strip of this character so arranged, would normally block or prevent inward swinging of the window, but by means of applicant's improved hinges, by which means the casement window is mounted in the casing, the window may be elevated in a vertical plane sufficiently to clear the stop strip 12 so as to permit inward swinging or hinging movements of the window.

One of the improved hinge members is shown in detail in Figs. 4, 5 and 6 and will be seen to comprise a plate portion 14 having apertures 15 therein for the insertion of attaching screws. Said plate member is further formed along one edge with a pair of

opposed rolled and tubular bosses 16. Between the bosses the stock of the plate is cut away to form a U-shaped recess 17. Said hinge member also includes a second plate member 18 formed with apertures 19 for the insertion of attaching screws and a side edge of said plate member is formed medially of its ends with a laterally projecting tubular rolled boss 20. Said rolled boss is of a length substantially equal to the combined length of the two bosses 16 on the plate 14 and is also of less length than the U-shaped recess 17. The two plate members 14 and 18 are hingedly connected together by means of a bolt or headed rod 21 which extends through the tubular bosses 16 and 20, the boss 20 being positioned between the bosses 16 in the recess 17 and aligned with the bosses 16. The unheaded end portion of the bolt or rod 21 is embraced by a bifurcated laterally offset inner end portion 22 of a clip member 23 and said bifurcated portion is hingedly or pivotally attached to the end portion of the bolt or rod 21 by a transverse stud 24. The outer end portion of the clip member 23 is formed as a laterally projecting U-shaped embracing member 25. In certain positions the embracing portion of the clip member is brought into engagement with a portion of the bolt or rod 21 between an end portion of the boss 20 and the adjacent end portion of a boss 16. Said embracing portion is of such dimensions as to take up the space between the adjacent ends of said bosses and when so engaged with the bolt or rod 21 the plate members are held with respect to each other and on the rod 21 in the manner shown in Fig. 4, whereby relative longitudinal movement between said plate members is prevented. On the other hand, if said clip member has its embracing portion 25 disengaged from the shank of the bolt or rod 21 and is permitted to extend or hang free thereof as in Fig. 5, relative longitudinal movement of the plate members 14 and 18 with respect to each other and on the bolt or rod 21 is permitted.

In the installation of the improved casement window and the improved hinges therefor, a pair of said hinge members are used, one being positioned relatively close to the lower portion of the window and the other being positioned relatively close to the upper portion of the window. The uppermost hinge is disposed in the manner of the hinge shown in detail in Figs. 4, 5 and 6 with the clip member being connected to the lower end portion of the bolt or rod 21. The plate member 14 of said hinge is connected to a suitable inner face portion of the casing 8 while the plate member 18 is connected to the inner edge of the window.

The lower hinge member is positioned reversely to the upper hinge member so that the clip member thereof is disposed at the

upper portion of said hinge, the plates of said hinge being connected respectively to the casing and the window. With this disposition of the two hinges when the clip member of the lowermost hinge is engaged on the bolt 21 between the uppermost boss 16 of said hinge and the boss 20, and when the clip member of the uppermost hinge is entirely disengaged and hanging free of the bolt member of its hinge, both hinge members are in a position wherein the lowermost disposition of one of their plates with respect to the other is permitted. In this position of the two hinges the casement window 11 is in its lowermost position of vertical adjustment with respect to the window casing and therefore seats on the stop strip 12 in the tight position shown in Figs. 1 and 3. Engagement of the clip member of the lower hinge with the bolt of the hinge will prevent upward movement of said window and therefore the window is effectively locked as it cannot be moved upwardly to clear the stop strip 12 so as to be opened inwardly. Also, if desired, as a co-operating lock member, the opposite side edge of the frame or sash of the window medially of its top and bottom edges may carry a shouldered plate 26 adapted to engage in the lowered position of the window with a recess in a complementary plate 27 carried by the window casing adjacent the window.

To open the window it is merely necessary to disengage the clip member of the lowermost hinge from the bolt 21 of the hinge and then by grasping a manipulating handle 28 mounted on the lower inner portion of the window frame and lifting upwardly on the window, upward vertical movement of the window is effected, as the parts of both hinge members may then move longitudinally upwardly with respect to other parts thereof, as previously described. It will be noted that clearance between the top edge of the frame of the casement window and the top portion of the window casing is provided, as indicated at 29 in Fig. 1, so as to permit this slight raising of the window. The upper inner edge portion of the window frame carries an upwardly projecting keeper strip 30 to prevent the entrance of weather when the window is in normal closed position.

After the window has been slightly elevated in a vertical plane, as afore-described, the clip member of the uppermost hinge is manipulated so as to engage the bolt of said hinge between the lowermost boss 16 and the boss 20 in the position shown in Figs. 2 and 4. As so vertically adjusted the window has been raised sufficiently far to clear the stop strip 12 and it may then be swung inwardly on the hinges 9 and 10.

From the foregoing description it will be seen that the improved casement window with the slidably hinges therefor permit a

very convenient and desirable disposition of the casement window so that the window may be swung inwardly which is desirable, and also permit the arrangement with the 5 stop strip to prevent entrance of weather. The longitudinally adjustable hinges are of novel construction and may be locked in their several positions of adjustment so that a window or other closure carried thereby may be 10 retained for swinging or hinging purposes in either a raised or lowered position. Furthermore, the improved casement window and hinges therefor are of simple and novel construction, require no undue modification 15 of a standard window casing, and are well adapted for the purposes set forth.

What I claim as my invention is:

1. A sliding hinge, comprising a pair of plates, a pivot bolt hingedly joining the same 20 and permitting sliding movement of one plate on said bolt and with respect to the other plate, and a latch member pivotally carried by said pivot bolt and positionable to engage said slideable plate and prevent sliding movement of the same.

2. A sliding hinge, comprising a plate having a pair of spaced apart laterally projecting tubular bosses, a second plate having an intermediate laterally projecting tubular 30 boss positioned between the bosses of the first plate and of less length than the space between the same, a pivot bolt extending through all of said bosses, and a latch member pivotally attached to the bolt and movable to engage an intermediate portion of the bolt between one boss of the first plate and the boss of the second plate.

In testimony whereof I affix my signature,
FRIDOLPH A. OLSON.
